IONIZATION CHAMBER

John J. Keyes, Jr., Newark, Del., assignor to the United States of America as represented by the United States Atomic Energy Commission

Application December 18, 1952, Serial No. 326,629

2 Claims. (Cl. 250—83.6)

The present invention relates to a gas flow ionization chamber for continuously monitoring a gas containing radioactive material.

Many laboratories today use radioactive isotopes for tracer analyses as well as radioactive sources of high intensity for other experimental work. There are facilities known as "hot" laboratories, usually associated with nuclear reactors, which deal primarily with irradiated materials, many of which are highly radioactive. Depending upon the materials under treatment, dangerous fission products, such as Xenon¹³³, may be released into the ventilating air of these laboratories, together with active particulate matter. The atmospheric tolerance level for Xe¹³³ is 2.0×10^{-7} microcuries per cubic centimeter. It is therefore essential that means be provided for detecting very low activities in the ventilating air to safeguard the working personnel from any accidental leaks of radioactive material.

It is apparent that a very sensitive detector is necessary to continuously monitor the ventilating air in these laboratories. The radioactivity in the air is measured in apparatus embodying the present invention by passing the ventilating air through the sensitive counting volume so that even the lowest activities will be measured. The difficulty with this procedure is that the internal parts of the ionization chamber, particularly the insulating portions, can become quickly contaminated and thereby require frequent disassembling for decontamination purposes.

A detector embodying the present invention prevents any such quick contamination as well as preventing leakage of the radioactive gas. If at any time, after a long period of use, the surfaces of the detector do become contaminated, the chamber can be quickly dismantled for decontamination purposes. The dismantling procedure is simplified by the absence of any complicated seals in the ionization chamber.

More particularly, the present invention relates to a gas flow ionization chamber for continuously monitoring radioactive gas which comprises a first electrode, a second electrode axially disposed within the first electrode and insulated therefrom, means for establishing a difference of potential between said electrodes to form a sensitive counting volume therebetween, shielding means enclosing said electrodes and spaced therefrom by electrically insulating spacers, means for introducing and expelling the radioactive gas to be measured from said sensitive counting volume, means for introducing a buffering non-radioactive gas into the space between the electrodes and said shielding means, the buffering gas being at a higher pressure than the radioactive gas and means for measuring any current flow between the first and second electrodes.

It is accordingly one of the objects of the present invention to provide a new and improved gas flow ionization chamber.

A second object of the invention is to provide a new

and improved quickly separable ionization chamber for continuously monitoring radioactive gas flow.

Another object is to provide an ionization chamber which protects the insulating surfaces thereof by use of a non-radioactive gas.

Still another object is to provide an easily separable ionization chamber which is inexpensive to fabricate and simple to maintain.

The many objects and advantages of the present invention may best be appreciated by reference to the accompanying drawing which is a transverse, sectional view of a preferred embodiment of the present invention shown in combination with diagrammatically represented conventional instruments.

Referring to the drawing, the apparatus is mounted within a stepped, cylindrical casing 10 having an upper annular flange 11 and a lower annular flange 12. Connected to the upper flange 11 is a plate 13 which seals the upper portion of casing 10 by means of a suitable gasket 14. Similarly, the lower portion of casing 10 is sealed by a base plate 16 and a gasket 17 attached to flange 12.

Also mounted on the base plate 16 are insulated spacers 18 which support a cylindrical chamber 20. Chamber 20 is preferably made of any suitable electrically insulating material, such as "Micarta," which is a laminated phenol formaldehyde. The entire inner surface of chamber 20 is coated with an electrically conductive coating 21 such as "Aquadag," which is a graphite coating.

Attached to the coating 21 at the upper end of chamber 20 is contact 25 connected to a conductor 22 which extends through the chamber and casing walls and is insulated from casing 10 by a plug 23 made of an electrically insulating fluorocarbon compound such as "Fluorothene." A conductor 35 connects conductor 22 to one side of a microammeter 24, the other side of which is connected to the electrical ground. The connection of conductor 22 to conductor 35 is shown diagrammatically so as not to unnecessarily complicate the drawing, but it is apparent to a person skilled in the art that this connection can be made in a conventional manner. For example, the conductor 35 may be removably clipped to conductor 22.

Centrally located in the upper end of chamber 20 is a passageway 26 through which extends a smaller diameter tubular member 30 made of an electrically insulating material. Member 30 extends substantially the entire length of chamber 20 and has its inner and outer surfaces coated with an electrically conducting material 27, such as "Aquadag." As indicated in the drawing, member 30 need only be coated up to a portion that is external to the chamber 20. Attached to the coating 27 in this portion is a second electrical contact 40 connected to a conductor 28 which extends up through plate 13 and is insulated therefrom by a plug 29. A conductor 31 connects conductor 28 to the movable arm of a potentiometer 32 which in turn is attached to the output of a conventional direct current power supply 33.

Tubular member 30 is maintained in a coaxial position with respect to chamber 20 and casing 10 by means of electrically insulating spacers 34. The inner surface 36 of the upper portion of casing 10 is preferably tapered, as shown, to properly support the tubing and spacer assembly. Holes are provided in spacers 34 to permit the passage therethrough of conductor 28.

Also mounted on the upper plate 13 is an inlet conduit 37 for the radioactive gas to be monitored. Conduit 37 extends partially within tubular member 30. At the lower end, conduit 37 is connected to a rigid wire 38 which is axially disposed with respect to member 30 and extends a substantial length therein.

Connected to the plate 13 and the stepped portion 39

of casing 10, respectively, are inlet conduits 41 and 42. Conduits 41 and 42 are connected to a gas supply 43 by means of conduits 44 and 46, respectively.

Mounted on the surface of casing 10 is an outlet conduit 47 for the radioactive gas. Conduit 47 extends through the surface of casing 10 and through an outlet passageway 48 in the surface of chamber 20 without touching the surface of chamber 20.

As indicated in the drawing, casing 10 is preferably made of an electrically conductive material which can be conveniently grounded at its lower flange by means of a conductor 49. The casing 10 and plates 13 and 16 therefore provide shielding means for the ionization chamber having cylindrical chamber 20 as its cathode and tubular member 30 as its anode. Since the inlet conduit 37 is mounted on plate 13 and the wire 38 is connected thereto, both conduit 37 and wire 38 are maintained at ground potential.

In operation, the inlet conduit 37 and the outlet conduit 47 are preferably mounted in series with the ventilating system to be monitored or a representative portion thereof. Potentiometer 32 on the output of power supply 33 is varied so as to supply the proper direct current potential to the cylindrical anode 30 of the ionization chamber. Since the "Aquadag" coating 27 on the inner surface of anode 30 is continuous about the lower end thereof, both the inner and outer surfaces of the anode are maintained at the desired D. C. potential.

As the radioactive gas flows through inlet conduit 37 down through anode 30, any static charge present in the gas will be removed by the grounded wire 38. As the gas flows upwards from the bottom of anode 30 to the outlet conduit 47 near the top of chamber 20, any ionization occurring in this volume due to the presence of a radioactive material will cause ions to impinge on the inner surface of cathode 20, that is, the positive ions will be repelled by the high positive D. C. potential present at the outer surface of anode 30. The potential of the coating 21 will be raised in proportion to the number of impinging ions. This change of potential is measured by meter 24. It is apparent that meter 24 can be connected to a conventional recording device if it is desired to obtain a permanent record of radioactive intensity of the gas in the ventilating system. Similarly, conventional alarm limits may be incorporated in meter 24 to operate when the reading corresponds to an intensity level equal to the tolerance level of 2.0×10^{-7} microcuries/cc. or less if desired.

The grounded casing 10 serves as a guard ring between the cathode 20 and the anode 30 so that leakage across the insulating spacers will not be recorded on the meter. As can be seen in a demountable apparatus of this type, the insulating surface could easily become quickly contaminated thereby providing a leakage path for stray currents so that the accuracy of the meter will become seriously affected.

To prevent this, a buffering non-radioactive gas is introduced from gas supply 43 through conduits 41 and 42 into the spaces between each of the electrodes and the casing 10. This buffering gas is preferably dry air or nitrogen and is maintained at a slightly higher pressure than that of the introduced radioactive gas. Since the outer diameter of conduit 37 is smaller than the inner diameter of anode 30, and the outer diameter of the anode 30 is in turn smaller than the inlet passageway 26 of chamber 20, none of the incoming radioactive gas will flow into the spaces between the casing 10 and the anode 30. Similarly, since the outer diameter of outlet conduit 47 is smaller than the diameter of passageway 48, none of the radioactive gas flowing out of the chamber 20 will flow into the space between casing 10 and chamber 20. That is, the non-radioactive gas acts as a buffer between the chamber's insulating surfaces and the radioactive gas.

Therefore, the chamber can be operated continuously for long time intervals without contaminating the guard ring and thereby providing a leakage path to upset the accuracy of the meter.

If it is necessary to repair or decontaminate the apparatus for any reason, the anode 30 may easily be removed by removing the plate 13. Similarly, the cathode 20 can be removed by removing the base plate 16. It can be seen that the dimensions are such that casing 20 could be slightly tilted to permit passageway 48 in cathode 20 to become free of conduit 47.

If the chamber is used in a ventilating system for a "hot" laboratory, it is preferable that the chamber be made in a comparatively large size so as not to impede the flow of ventilating air. One embodiment which operated satisfactorily used a cathode with a 10-inch internal diameter and a length of 40 inches. The diameter of the anode was $1\frac{1}{4}$ inches, whereas the overall length of the apparatus was approximately 55 inches. This apparatus used a D. C. potential of 250 volts and also used a Beckman RXG-2 micro-microammeter. This chamber gave a response of 5×10^{-14} amperes for 10^{-13} curie/cc. of Xe^{133} .

Since many embodiments of the present invention might be made and since many other changes may be made in the preferred embodiment described above, it is understood that the foregoing description is to be interpreted as illustrative only and not in a limiting sense except as required by the appended claims.

I claim:

1. A separable ionization chamber for continuously monitoring a radioactive gas which comprises in combination, an electrically conductive base plate, a cylindrical chamber mounted in insulated relation thereon and having a passageway in one end thereof, a tubular member mounted coaxially with said chamber and extending through said passageway substantially the length of said chamber, the outer diameter of said tubular member being smaller than the diameter of said passageway, a stepped, cylindrical, grounded casing mounted on said base plate and completely enclosing said chamber and tubular member, an inlet conduit for said radioactive gas mounted on said casing and coaxially extending within one end of said tubular member, the outer diameter of said conduit being smaller than the inner diameter of said tubular member, an outlet conduit for said radioactive gas mounted on said casing surface and extending through a second passageway in the surface of said chamber, the outer diameter of said conduit being smaller than the diameter of said second passageway, means for introducing a buffering non-radioactive gas into the space between said casing and said chamber and tubular member, said buffering gas being at a higher pressure than said radioactive gas, means for establishing a difference of potential between said tubular member and the inner surface of said chamber, and means for measuring the number of ions reaching the inner surface of said chamber.

2. Apparatus as recited in claim 1 in combination with means for removing a static charge in the introduced radioactive gas.
